SECTIONAL SOFA

Hubert Howard Watson and Mike Stewart Watson, Galax,
Va., assignors to Sawyers Furniture Company, Galax,
Va.

Filed Feb. 28, 1972, Ser. No. 230,206

Term of patent 14 years

Int. Cl. D6—01

U.S. Cl. D6—46

FIG. 1

FIG. 2

FIG. 3

FIG. 4

FIG. 5

FIG. 6

FIG. 1 is a perspective view of a sectional sofa showing our new design;

FIG. 2 is a left end elevational view of the section shown at the left of FIG. 1;

FIG. 3 is a right end elevational view of the section shown at the right of FIG. 1;

FIG. 4 is an enlarged fragmentary view of the front corner of the section shown at the left of FIG. 1;

FIG. 5 is an enlarged fragmentary view showing the ornamentation located along the bottom front surface of the sectional sofa of FIG. 1; and

FIG. 6 is a rear elevational view of the section shown at the right of FIG. 1.

The back of the sectional sofa shown is substantially plain and unornamented.

We claim:

The ornamental design for a sectional sofa, as shown and described.
